UNITED STATES PATENT OFFICE

JOSEPH H. GIESKE, OF ST. PAUL, MINNESOTA, ASSIGNOR OF ONE-THIRD TO EUGENE F. RODDY, OF ST. PAUL, MINNESOTA

SLUG DETECTOR

Application filed August 12, 1927. Serial No. 212,464.

My invention relates to slug detectors wherein it is designed to provide a simple, yet very effective means of detecting slugs for money slot machines or for any machine using coins for operating the same.

It is a feature of my invention to provide a means having a primary and a secondary testing mechanism so as to detect a slug before the same enters the coin machine, thus preventing the operation of the coin machine by either a light or a heavy slug and virtually preventing the operation of the coin operating machine by anything except the proper coin for that particular machine.

My detector is provided with a means of locking the same to prevent operation by jarring or tampering when a slug has been used in the detector. The primary and important feature of my detector includes a means and mechanism for insuring the detecting of slugs and preventing them from entering the coin machine.

These features together with other objects and details of the invention will be more fully 25 and clearly set forth in the specification and claims.

In the drawings forming part of this specification:

Figure 1 is a sectional front view of my detector as it would appear in use, the front face 30 of the cover being removed.

Figure 2 is an end view of the same.

Figure 3 is an end view showing the cover of the detector removed to illustrate the parts 35 within the detector.

Figure 4 is a plan view of my detector.

Figure 5 is a front view showing the parts in a different position.

Figure 6 is a detail of a portion of the detector.

In the drawings my detector A is provided with a cylindrical housing or casing 10 which is adapted to be supported by the brackets 11 in a suitable manner attached rigidly to the 45 coin machine B, only a portion of the coin machine B being illustrated in the drawings.

The casing 10 is provided with a door 12 on one side of the same which is adapted to fit over the staple 13 so that a lock can be passed 50 through the staple 13 to hold the door closed.

Obviously any suitable locking means may be provided for the cover 12.

The slug detector A is provided with a primary balance C which is formed by the balance arm 14 pivotally mounted in the casing 55 10 by the shaft 15. One end of the balance arm 14 is provided with an adjustable balance weight 16 carried on the screw 17 which is supported by the bracket 18 to the arm 14.

The other end of the balance arm 14 is provided with a coin receiving slot 19 extending through the guard plate 20 which projects upwardly from the coin receiving end of the balance C. Normally the balance C has its arm 14 extending in the position illustrated 60 in Figure 1 with the weight end resting against the lug 21 and depending from the pivot point 15 while the coin receiving end projects upwardly so that the slot 19 coincides with the slot 22 in the outer front face 65 of the casing 10 so as to receive a coin through the slot 22 of the casing and through the slot 19 to the coin receiving end of the balance C.

I provide a secondary balance D in the detector A which is pivotally attached at 24 to 70 the ears 25 and is provided with a chute-like portion 26 in which the coins are adapted to slide in passing over the secondary balance D. This secondary balance D is provided with an adjustable weight member on the screw 27 75 80 which is supported by the arm 28 so that the same can be properly balanced for the desired coin.

When the balance C receives a coin or a slug which is of the proper weight to operate 85 it it will drop automatically into position to bring the slot 19 in line with the slot 29 in the back wall of the casing 10 and this slot 29 is in line with the opening of the chute 26 so that the coin carried by the balance C may be pushed from the balance through the slot 29 on to the chute 26.

The coin machine B, only a portion of which is illustrated, is provided with a coin 95 receiving end 30 having a coin opening 31. The coin detector A is attached to the coin machine B in a manner so as to cause the chute 26 to be positioned so that when a coin slides down the chute 26 it is adapted to drop 100.

into the opening 31 and from there into the coin machine B so as to operate the same.

I have provided a shelf 32 adjacent the free end of the chute 26 so as to provide a means of receiving a slug which is too heavy for the setting of the balance D to prevent the slug from sliding into the opening 31 as it is heavier than the coin for which the balance D is set. This secondary balance D is adapted to be set so as to remain in position to slide the proper weight coin for operating the machine B directly into the opening 31, however, if a slug of a heavier nature than the coin enters the chute 26, the free end of the chute 26 will immediately drop to deposit the slug on the shelf 32 and stop the operation of the detector. The proprietor or owner of the machine B may then open the cover 12 and remove the slug from the shelf 32.

20 The detector A is provided with a locking means E which is pivotally supported on the back of the casing 10 by the rod 35. This rod is supported to the casing and the locking means E is covered by a suitable casing portion projecting over the same. The locking means E is in the form of a rod bent with a center eye portion 36 which fits over the upwardly projecting end of the rod 35 to pivotally support the lock and one end of the lock 25 is provided with an arm 37 having inwardly projecting lugs 38 adapted to be normally positioned as illustrated in Figure 4 adjacent the opening 39 so that the end 38 may project into the opening 39 and engage with the 30 weight end of the balance arm 14. The other end of the lock E is provided with an arm 40 which is formed with an inwardly projecting portion 41 extending through the slot 42 into the casing 10 and the portion 41 is provided with an upwardly extending arcuated end 43.

When the balance C is operated by a coin in the normal ordinary manner, the balance arm with the slot 19 drops down to line up 45 with the slot 29 and as the balance drops by the weight of the proper coin the end 43 of the lock E is engaged and the lock is dropped to permit the balance C to operate properly with a coin so that the coin may be 50 pushed from the operating end of the balance through the slot 29 and on to the chute 26. However, if a slug is inserted through the slot 22 and the slot 19 on to the balance C which is too light, the balance C will not be 55 operated.

I provide a coin pusher arm 46 which extends in line with the slot 29 and which is adapted to be pushed inwardly to operate the detector A when the balance C receives the 60 coin through the slot 22. Thus when a light coin is placed on the balance C it will not operate the same and when the operator who has placed the coin on the balance C operates the coin pusher arm 46, the same will strike 65 the arcuated portion 43 of the locking means

E causing the lug 38 of the same to pass through the opening 39 and engage the balance arm 14 to lock the same against operation by jarring or tampering. It is then necessary for the proprietor to open the cover 12 and remove the slug before the detector can be cleared just as is true when too heavy a slug is received in the machine and it comes up to the secondary balance D as is hereinbefore described.

The detector A is of a simple construction and can be adapted to any coin operating machine so as to cover the coin receiving slot and place the secondary balance D in line with the same so that virtually no slug can be passed through the detector without being detected either by the primary balance C or the secondary balance D. The primary balance C detects the light coins by remaining inoperative and the operation of the coin pusher 46 operates the locking means E to lock the balance C against operation while the secondary balance D detects the heavy slugs which obviously will operate the balance C to drop the slugs into line with the slot 29 but the detector balance D will stop the slug from entering the coin machine opening 31 by dropping the balance D so that the slug will strike on the shelf 32. In this manner I have provided a slug detector having a double assurance of picking up light and heavy slugs and including balancing means which is adjustable to the desired coin so as to give an operative device of a very practical nature.

In accordance with the patent statutes, I have described the principles of operation of my slug detector and while I have illustrated in the drawing a particular formation and construction of the parts, together with a certain design of the same I desire to have it understood that ordinary changes may be made within the scope of the following claims without departing from the spirit of my invention.

I claim:

1. A slug detector including, a primary and a secondary balancing means adapted to detect light and heavy slugs and manual means for transferring objects from said primary to said secondary balancing means.

2. A slug detector including a balancing member, means for adjusting said balancing member, a coin slot to said balance, a secondary balance, a coin slot to said secondary balance and a coin pusher adapted to push the coin from said first balance to said secondary balance to cause the coin to be balanced through the detector before entering a coin operated machine.

3. A detector for slugs adapted to be attached to a coin machine including, a primary balance, means for adjusting said balance, a secondary balance, means for adjusting said secondary balance and outside coin openings

to said first and secondary balances to permit a coin to be passed from the first balance to the second balance to provide a double weighing of the coin to detect slugs.

5. A detector for coin operated machines including, means set to balance to the lightest weight of coin that may be used, means set to balance for the heaviest coin that may be used in the operation of the coin machine, whereby a light or heavy weight coin may be detected to eliminate slugs from entering the coin machine and manually operated transferring means between said balancing means.

10. 6. A detector for slugs comprising an adjustable balance for light weight coins, an adjustable balance for heavy weight coins and a lock adapted to lock said light weight balance to prevent operation of the same when a light weight imitation coin is inserted in said detector.

15. 7. A detector for a coin operated machine adapted to eliminate slugs including means adapted to detect a light weight slug, means adapted to detect a heavy weight slug to prevent the same from entering the coin machine and means to prevent further operation of the machine when a light weight slug is placed in said light weight slug detecting means.

20. 8. A detector for coin operated machines including, a casing, a coin receiving balance within said casing, an adjustable balance weight, a secondary balance associated with said casing and first balance adapted to provide a coin chute for receiving coins from said first balance, an adjustable balance weight for said secondary balance, a shelf adjacent the free end of said secondary balance adapted to receive articles from said chute balance too heavy for the operation of the coin machine and locking means for said first mentioned balance.

25. 9. A slug detector for coin operated machines including, a primary and secondary balance, adjustable means for each of said balances, connecting slots, a lock for said first balance, a guard carried by said first balance adapted to close the receiving slot of said detector, said first balance being adapted to detect light weight slugs and said second balance being adapted to detect heavy slugs.

30. 10. A slug detector including, a housing, a balance receiver within said housing, a slot leading to the receiving end of said balance, a guard for closing said slot when said balance is operated, a second slot adapted to be in line with said receiving end of said balance when said balance is operated, a secondary balance adjacent said second slot, and a shelf adjacent the free end of said secondary balance to receive heavy slugs carried from the first to the second balance.

35. 11. A slug detector comprising, a housing, a balance member within said housing adapted to be set to detect a light weight slug, a

guard carried by said balance member, a secondary balance adjacent the free end of said first balance adapted to detect heavy weight slugs, a lock pivotally interposed between said balances having means adapted to operate the same to lock said first balance against operation when a light weight slug is applied thereto in the operation of said detector.

40. 12. A slug detector including, a primary balance adapted to detect light weight slugs, a secondary balance associated with said first balance adapted to detect heavy slugs, means for balancing said balance members, a coin pusher, a locking means for interrupting the operation of said primary balance, said locking means including an arm intersecting the path of operation of said coin pusher, whereby said locking means is operated by said coin pusher to lock said primary balance when a light weight coin or slug is introduced into said detector.

45. 13. A slug detector comprising, means for detecting light weight slugs, means for locking said detecting means when a light weight slug is inserted therein, and a door for access to said detector to remove the light weight slug and to reset the operating parts of said detector.

50. 14. A detector including, means for detecting a light weight slug, means for detecting a heavy weight slug; and a lock adapted to be operated to hold said means for detecting a light weight slug inoperative when a light weight slug is inserted in said detector and the detector is operated.
